UNITED STATES PATENT OFFICE

HENRY W. ST. PIERRE, OF TORRINGTON, CONNECTICUT

RIVET FORMER AND HEADER

Application filed January 29, 1930. Serial No. 424,257.

This invention relates to a machine for forming and heading rivets, particularly to a die for use in such machine for automatically forming and heading tubular or split rivets, and has for a special object to provide a die which will automatically form and head the tubular or split rivet and then eject it from the die.

With this and other objects in view, the invention consists in certain novel features of construction, combinations and arrangements of parts as will be more fully disclosed in connection with the accompanying drawing.

In this drawing

Fig. 1 is a longitudinal section through a die construction involving my invention and showing the mounting and operating means diagrammatically, the parts being in the position they occupy during the first part of the operation of forming a rivet.

Fig. 2 is a section of the opposed ends of the die and heading punch showing their positions after the blank has been cut off and carried to its position in front of the die.

Fig. 3 is a section similar to Fig. 1 showing the position of the elements at the completion of the operation of forming and heading the rivet.

Fig. 4 is a similar section showing the rivet forced out of the die.

Fig. 5 is a side elevation of the punch pin for forming the recess in the end of a split rivet, and

Fig. 6 is a side elevation of such a rivet.

Tubular or split rivets are very desirable for certain types of work as they are more easily manipulated than solid rivets and also make a better appearing finished job. These tubular rivets have a recess in the free end thereof extending for a given distance from the free end of the shank opposite to the head making this free end tubular, the remainder of the shank being solid, while in a split rivet the recess extends entirely across the shank in this same free end, as shown in Fig. 6. Both types of rivets can be made with the same mechanism, it being merely necessary to change the shape of the punch for forming the recess. At the present time, it is common practice to head the rivets in one

operation and drill the recess in the free end of the shank by means of rotary drills in a separate operation. This is expensive as production is relatively low, requires more machinery and handling for the two operations, and there is high material and labor cost for the drills and keeping them sharp. Furthermore, with the use of certain metals for forming the rivets, such for example as aluminum, this drilling operation is very difficult if not practically impossible for production purposes, because unless the drills are kept extremely sharp, they tear the metal or clog up so as to tear the metal. It has been proposed to punch the recess in the end of the rivet shank, but this has not been successful because up to the present time, so far as I am aware, there has been no means of automatically ejecting the finished rivet from the die.

In the present construction, I have formed a die and mechanism which not only automatically forms and heads the tubular and split rivet by punching the recess in the end of the shank, but also automatically ejects the finished rivet from the die, so that the rivets are formed complete in a single operation on a single machine, the drilling operations are done away with and practically any metal desired can be used for the rivets. Furthermore, the complete rivets can be formed at practically the same speed at which in former operations, the heading alone was accomplished.

I have shown in the drawing one construction of mechanism for automatically forming, heading and ejecting the rivets, and have shown merely diagrammatically the means for operating it. The die shown can be used with a standard type of heading machine and comprises a die block or body 10 mounted in the present instance in the stationary frame or bed 11 of the machine. The die is seated in a recess or pocket 12 in the frame and secured therein by any suitable means such as a set screw 13. At its inner end it may rest against the shoulder 14 so the force incident to the forming of the rivet is transmitted directly to the frame instead of being carried by the set screw. The die 10 has an opening

or passage 15 extending from the outer end thereof and of a size to receive the shank 16 of the rivet, and mounted to slide in this passage is a sleeve 17, preferably provided with a head 18 to limit its forward movement in the passage and prevent its moving out of the passage. At its inner end, the passage opens to an enlargement 19 in which the head 18 is located. Mounted to slide within the sleeve 17 is a punch pin 20 having its free end 21 of a shape to form the recess in the end of the rivet shank. If it is desired to form a tubular rivet as shown in Figs. 1 to 4, the end of this pin will be of smaller diameter than the shank of the rivet, but if it is desired to form a split rivet as shown in Fig. 6, the end of the punch pin will then be shaped accordingly and will be more or less flattened or tapered as shown at 21' in Fig. 5.

In the present construction there is carried on pin 20 a second sleeve or head 22 which may be either rigidly attached to the pin 20 or loose thereon, but in conjunction with the operating mechanism movable with the pin, and its inner end 23 of sleeve 22 forms a shoulder to engage the inner end of the sleeve 17 and also to operate the sleeve 17 in a manner that will later be described. Surrounding the sleeve 22 is a coiled compression spring 24 engaging at one end the inner end of the sleeve 17 and at its opposite end under the head portion 25 of the sleeve 22. This spring, therefore, tends to shift the sleeve 22 away from the sleeve 17 and also to carry with it punch pin 20, and therefore, to shift this pin 20 away from the rivet. Because of this operation, the pin 20 may be headed as shown at 26 so that the pin is carried with the sleeve 22. The pin and sleeves are operated by a slidable rod or plunger 27 mounted to reciprocate in the frame or bed and operated by any suitable means such as a lever 28 pivoted at 29 and operated by a rod 30 from a cam 31 on a suitably driven shaft S. This shaft may also carry a crank 32 connected by a pitman or connecting rod 33 with any suitable toggle 34 for reciprocating the gate 35. Mounted in this gate is the punch 36 having a recess 37 in its forward end shaped to form the head 38 of the rivet. This operating means for the plunger 27 and gate 35 are shown merely diagrammatically as they may be of any desired type.

In operation, the blank 16 shown in Figs. 1 and 2 is cut from a wire or rod of the desired size and metal and fed to a position between the punch 36 and die 10 by any suitable type of cut-off and feed mechanism, not shown, such as is used with the ordinary heading machines. In the present instance, the punch 36 is moved away from the die to permit the blank 16 to be fed to a position in front of the passage 15. The gate 35 then advances so that the punch 36 engages the outer end of the blank and starts to force it

into the end of the passage 14 and force back the sleeve 17 as shown in Fig. 2, at which time the feeding mechanism is withdrawn as is the usual practice in heading machines. As the punch 36 advances, the sleeve 17 and punch pin 20 are first forced backwardly into die 10 as indicated in Fig. 1, and then the plunger 27, being controlled by the cam 31 advances the punch pin 20 relative to the sleeve 17 against the end of the blank 16 or holds it comparatively stationary as the rivet and sleeve 17 are forced backwardly and forces the end 21 of this pin into the end of the rivet shank as indicated in Fig. 1. As the pin 20 advances, relative to the sleeve 17, the sleeve 22 moves with it compressing the spring 24 which holds the smaller end of the sleeve 17 against the end of the rivet shank. As the end of the pin 20 is forced into the end of the rivet, the shoulder 23 on the sleeve 22 advances relative to sleeve 17 until it engages the inner end of the sleeve 17 as indicated in Fig. 3. This will then prevent further backward movement of the sleeve 17 and the rivet blank 16 and, therefore, the co-acting pressure and blow between the punch pin 20, the sleeve 17 and the heading punch 36 will form the head 38 on the rivet as well as form the punched recess 39 in the free end of the shank. The rivet is now completely formed with the head 38 and the recess 39 as shown in Fig. 3.

The heading punch 36 now begins to move away from the die 10, and the plunger 27 is further advanced by the cam 31. This movement of the plunger 27 advances the pin 20 and sleeve 17 to force the rivet out of the passage 15 in the die as indicated in Fig. 4. After the rivet is forced out of the die, the lever 28 moves in the opposite direction and permits the spring 24 to force the sleeve 22 and pin 20 backwardly or in the opposite direction, which is to the left as shown in Fig. 4. During this movement, the spring holds the sleeve 17 in the position of Fig. 4, while the pin 20 is drawn backwardly to remove its punched end 21 from the recess 39 in the rivet. The rivet then merely drops out from the position between the punch 36 and the die 10, a new blank 16 is fed into position, the punch 36 comes forward and the operation is repeated. It will, of course, be obvious that as the operation depends on relative movement between the die and punch 36, the punch 36 may be the stationary member and the die moved, or both may be moved in certain timed relation to give the desired operation. Also, this device can be used either in a single or double blow header.

In order to make the split rivet as shown in Fig. 6 which has a transverse recess 40 in the end of the shank, it is merely necessary to shape the punch end of the pin 20 to correspond as shown at 21' in Fig. 5. Otherwise, the operations are the same in forming this

rivet as forming the tubular rivet as described in connection with Figs. 1 to 4.

It will be obvious from the foregoing description that the rivet is formed, headed, the recess punched in the end of the shank and the finished rivet is forced out and dropped from the die entirely automatically and in a single operation. No separate operations of drilling are, therefore, required; production is greatly increased and cost is greatly reduced. Furthermore, the rivets can be made from practically any metals desired.

Having thus set forth the nature of my invention, what I claim is:

- 15 1. In a rivet former and header, a stationary die having an internal passage to receive the shank of the rivet, a heading punch having a recess to form a head movable toward and from said die, a sleeve slidable in said passage, a punch pin slidable in said sleeve to form a recess in the end of the rivet shank, a spring tending to withdraw the pin from the rivet, a shoulder movable with the pin to engage an abutment on the sleeve to limit movement of the pin in the sleeve in the opposite direction and to shift said sleeve to force the rivet out of the die, and means for operating the pin in timed relation with the operation of the heading punch.
- 20 2. In a rivet former and header, a stationary die having an internal passage to receive the shank of the rivet, a heading punch having a recess to form a head movable toward and from said die, a sleeve slidable in said passage adapted to cooperate with said punch to upset a head on the rivet, a punch pin slidable in the sleeve and adapted to form a recess in the end of the rivet shank, means movable with the punch pin to limit movement of the sleeve in one direction and means to operate the sleeve, pin and punch in timed relation to form the rivet and then to advance the sleeve to force the rivet out of the die.
- 25 3. In a rivet former and header, a stationary die having an internal passage to receive the shank of the rivet, a heading punch having a recess to form a head movable toward and from said die, a sleeve slidable in said passage, means to limit movement of the sleeve in the passage, a punch pin slidable in said sleeve and capable of forming a recess in the end of the rivet shank, means to operate the sleeve, pin and punch in timed relation to form the rivet and then advance the sleeve to force the rivet from the die, and means to withdraw the pin from the rivet.
- 30 4. In a rivet former and header, a stationary die having an internal passage to receive the shank of the rivet, a heading punch having a recess to form a head movable toward and from said die, a pair of relatively movable means in said passage one of which co-operates with said punch to form a head on

one end of the shank and the other of which co-operates with the punch to form a recess in the opposite end of the shank, and means for then advancing the first of said pair of means to force the rivet from the die.

5. In a rivet former and header, a die having an internal passage to receive the shank of the rivet, a heading punch having a recess to form a head, means for causing relative movement between the punch and die toward and from each other, and means in said passage to cooperate with said punch to form a head on one end of the shank and a recess in the other end thereof and then forcing the rivet from said passage, said means including a sleeve and a punch pin operating through the sleeve, said punch pin carrying means to engage and hold the sleeve and then move it to force the rivet from the passage.

6. In a rivet former and header, a die having an internal passage to receive the shank of the rivet, a heading punch having a recess to form a head, said punch and die being capable of relative movement toward and from each other, a sleeve slidable in said passage, a punch pin slidable in said sleeve and capable of forming a recess in the end of the rivet shank, means movable with the pin to limit movement of the sleeve inwardly of the recess, means to operate the sleeve, pin and punch in timed relation to form the rivet and then cause relative movement between the sleeve and die to force the rivet from the passage, and means to withdraw the pin from the rivet.

7. In a rivet former and header, a die having an internal passage to receive the shank of the rivet, a heading punch having a recess to form a head, means for causing relative movement between the punch and die toward and from each other, a pair of relatively movable means in said passage to cooperate with said punch to form a head on one end of the shank and a recess in the opposite end thereof, and means for then advancing one of said pair of means in the passage to force the rivet out of the die.

8. In a rivet former and header, a die having an internal passage to receive the shank of the rivet, a heading punch having a recess to form a head, means for causing relative movement between the die and punch toward and from each other, a sleeve slidable in said passage, a punch pin slidable in said sleeve capable of forming a recess in the end of the rivet shank, a spring tending to withdraw the pin from the rivet, a shoulder movable with the pin to engage an abutment on the sleeve to limit movement of the pin in the sleeve toward the rivet and to shift said sleeve to force the rivet out of the die, and means to operate the pin in timed relation with the relative movement between the die and punch.

9. In a rivet former and header, a die hav-

- ing an internal passage to receive the shank of the rivet, a heading punch having a recess to form a head, means for causing relative movement between the die and punch toward and from each other, a sleeve slidale in said 5 passage, means on the sleeve to limit its movement in one direction, a punch pin slidale in said sleeve capable of forming a recess in the end of the rivet shank, means 10 for withdrawing the pin from the rivet, means movable with the pin to limit relative movement of the pin in the sleeve toward the rivet and to shift the sleeve in the passage to force the rivet out of the die, and means to operate 15 the pin in timed relation with the relative movement between the die and punch.
10. A die for a rivet former and header comprising a body having a passage therein to receive the shank of a rivet, a sleeve slid- 20 able in said passage and adapted at one end to engage the end of the shank, a punch pin slidale in the sleeve and capable of forming a recess in the end of the rivet shank, a spring tending to withdraw the pin from the rivet, 25 and a shoulder movable with the pin normally spaced from the sleeve and adapted to engage said sleeve to limit relative movement of the pin in the sleeve.

In testimony whereof I affix my signature.
